UNITED STATES PATENT OFFICE.

BERTNIE M. WILHITE AND FRANK A. HOYT, OF GORDON, NEBRASKA.

TRUNK-HANDLE.

SPECIFICATION forming part of Letters Patent No. 655,039, dated July 31, 1900.

Application filed November 11, 1899. Serial No. 736,623. (No model.)

To all whom it may concern:

Be it known that we, BERTNIE M. WILHITE and FRANK A. HOYT, citizens of the United States, and residents of Gordon, in the county of Sheridan and State of Nebraska, have invented a new and Improved Trunk-Handle, of which the following is a full, clear, and exact description.

The purpose of this invention is to provide a trunk-handle which when under strain will be forced away from the trunk, thus avoiding cramping a person's hand against the trunk, which inconvenience results from the use of trunk-handles as ordinarily constructed.

15 This specification is the disclosure of one form of our invention, while the claim defines the actual scope thereof.

Reference is to be had to the accompanying drawings, forming a part of this specification, 20 in which similar characters of reference indicate corresponding parts in all the views.

Figure 1 is an end view of a trunk to which our invention has been applied. Fig. 2 is an enlarged elevation of the invention. Fig. 3 25 is a longitudinal section on the line 3 3 of Fig. 2. Fig. 4 is a detail section of the handle proper on the line 4 4 of Fig. 2, and Fig. 5 is a perspective view of one of the housings in which the ends of the handle proper are 30 mounted.

The strap or handle proper of the device comprises a steel or other resilient core-plate *a*, fitted between covering portions *b*, formed, preferably, of leather. The coverings *b* overlap the core *a*, and the edges of the coverings 35 are secured together by stitching *b'*, as shown. The ends of the core *a* project beyond the coverings *b* and are formed with bearings *a'*, in which are secured pins *a''*, the ends of which 40 are headed and projected beyond the edges of the handle or strap proper. Each end of the strap is provided with a ferrule or other covering *a''*, which ferrules are formed of metal plates bent over the end portions of 45 the strap and riveted thereto, as shown.

Secured rigidly to the trunk by means of fastening devices extending through its feet *c* are housings *c*. These housings receive the respective ends of the strap and are formed 50 in each side wall with diagonal slots *c'*, which slots respectively receive the end portions of the rods or pins *a'*, the heads of such pins lying outside of the housings, as shown. It

should be understood that the heads of the pins *a'* may be formed in any desired manner 55 by which to enable the pins to be placed in position in the housings *c* and bearings *a'*. The slots *c'* of the housings are disposed toward each other, as shown best in Fig. 3, and the outer walls of the housings are preferably 60 inclined, as also illustrated in this view.

The spring-core *a* of the handle or strap proper causes the handle proper normally to assume the position shown in full lines in Fig. 3, in which the core is straightened out and 65 the pins *a''* caused to lie in the inner portions of the slots *c'*. When, however, the strap is grasped and drawn outward, as indicated by the dotted lines in Fig. 3, the pins *a''* will be caused to move in the diagonal slots *c'*, to the 70 outer ends thereof, and this will have the effect of bowing the strap, as indicated by the dotted lines in the view referred to, thus holding it away from the trunk as long as the strap is under strain, which operation avoids forcing a person's hand against the trunk, as explained hereinbefore.

While we have shown and described our invention as particularly applicable to trunks, it will be evident that it may be applied to 80 tool-chests or to any other article of that character requiring a handle.

Having thus described our invention, we claim as new and desire to secure by Letters Patent—

A trunk-handle, comprising a spring-strap, pins secured to the ends thereof and projecting transversely beyond the same, and housings secured to the trunk, in which are received the ends of the strap, the housings being formed with slots or guideways inclined with respect to the trunk and projected toward each other and the pins being mounted to move in the slots or guideways so that outward strain on the handle will cause the end portions to move diagonally outward and toward each other, thus bowing outward the spring-strap. 95

In testimony whereof we have signed our names to this specification in the presence of 100 two subscribing witnesses.

BERTNIE M. WILHITE.

FRANK A. HOYT.
